F. A. WILLIAMS.
COMBINED SAFETY AND BOLT LOCK FOR GUNS.
APPLICATION FILED FEB. 14, 1919.

Patented Oct. 14, 1919.

UNITED STATES PATENT OFFICE.

FRANK A. WILLIAMS, OF DETROIT, MICHIGAN.

COMBINED SAFETY AND BOLT LOCK FOR GUNS.

1,318,423.

Specification of Letters Patent.

Patented Oct. 14, 1919.

Application filed February 14, 1919. Serial No. 276,944.

To all whom it may concern:

Be it known that I, FRANK A. WILLIAMS, a citizen of the United States of America, residing at Detroit, in the county of Wayne 5 and State of Michigan, have invented certain new and useful Improvements in Combined Safety and Bolt Locks for Guns, of which the following is a specification, reference being had therein to the accompanying 10 drawings.

The invention relates to guns of the bolt action type and has particular reference to constructions in which the rear sight is mounted above the bolt. It is the primary 15 object of the invention to obtain a construction of safety which does not interfere with the sight mounting. And further to obtain a construction which performs auxiliary functions as hereinafter set forth.

20 In the drawings:

Figure 1 is a side elevation of a bolt action gun, showing the rear sight mounted above the bolt and provided with my improved safety;

25 Fig. 2 is a rear elevation of the bolt and sight;

Fig. 3 is a similar view of the sight detached;

Fig. 4 is a plan view of the sight;

30 Fig. 5 is a longitudinal section thereof; Fig. 6 is a cross-section;

Fig. 7 is a longitudinal section through the sight, sleeve, firing pin and safety assembly detached;

35 Fig. 8 is a cross-section thereof in the central plane of the safety;

Fig. 9 is a horizontal section;

Fig. 10 is a plan view showing the relation of the safety and bolt lock;

40 Fig. 11 is an end elevation of the bolt lock;

Fig. 12 is a cross-section through the bolt in the plane of the lock.

A is the gun stock, B the frame, C the bolt, D the actuating bolt handle, E the sleeve, and F the firing pin of a standard bolt action assembly. G is a rear sight assembly which is mounted upon the sleeve E, but which is also provided with a bearing 45 portion H for slidably engaging the frame so as to accurately position the sight. The construction of the sight assembly forms no part of the present invention, but as shown comprises a leaf frame I which is pivotally and laterally adjustably mounted

on the shaft J in the bifurcated bracket member K, while a vertically adjustable spring frame L engages the leaf and carries the peep sight M.

The mounting of this sight above the 60 sleeve interferes with the use of a rockable safety such as are provided on standard bolt actions, and I have therefore devised a safety of the following construction: N is a bar which slidably engages a transverse 65 aperture in the sleeve between the mounting for the sight and the firing pin. Upon the lower face of this bar are the projecting ribs or teeth O adapted to engage corresponding ribs or teeth P on the firing pin. 70 The bar N is of greater length than the bearing in the sleeve so that it can be adjusted in position by pressure on the projecting end into any one of three different positions. The lower surface of the safety 75 is also cut away at Q so as to permit, in one position of its adjustment, the free movement of the firing pin, while in the other positions of adjustment the engagement of the teeth O and P will lock said firing pin. 80 The entering ends of the teeth O are slightly beveled at O' so that in engaging with the teeth P the pin F is slightly retracted. This has the effect of withdrawing the cocking 85 nose R, so that in case the sear is withdrawn it can return again into position for engagement with the firing pin.

The safety N is held in its several positions of adjustment by a spring pressed detent S which is arranged in a longitudinal 90 bore in the upper portion of the sleeve E. This detent S also performs the function of a bolt lock and to this end comprises a hollow member S' and a pointed nose member S² at one end thereof. S³ is a cross pin engaging an elongated slot S⁴ in the member S', and S⁵ is a spring within the hollow member interposed between the pin S³ and the nose piece S². The safety N is formed with a notch T for engaging the nose piece S² 100 when in one position of adjustment, in which position the opposite end of the member S' is projected beyond the bore and into engagement with a recess U in the bolt so as to lock the bolt from turning. The safety 105 N is further provided with a groove T² into which the nose piece S² is forced by the tension of the spring S⁵ when said safety is in the second or third position of adjustment. In either of these latter two posi- 110

tions the member S' is retracted into the bore and is thereby withdrawn from engagement with the recess U, permitting the turning of the bolt.

5 With the construction just described, to place the mechanism on safety and also to lock the bolt from operation, the member N is in the position shown in Figs. 7 to 10. It will be noted that in this position the nose 10 piece S² being in engagement with the notch T will hold the member N with the teeth O in full engagement with the teeth P, and therefore the firing pin is locked from movement within the sleeve. At the same time 15 the member S being projected into engagement with the notch U prevents the rotation of the bolt. If it is desired to release the bolt and at the same time to continue the locking of the firing pin, the member N is 20 adjusted to its intermediate position, where the nose piece S² is in engagement with the slot T². The teeth O and P are still in engagement with each other so that the firing pin is locked, but the movement of the nose 25 piece S² into the slot T² permits the spring S⁵ to withdraw the projecting end of the member S', disengaging the same from the notch U and freeing the bolt for rotation. Thus, the operator is permitted to remove 30 the bolt while the firing pin remains locked. In the third position of adjustment the cut away portion Q of the member N registers with the firing pin, so that the latter is free to move whenever released by the sear and 35 the gun is consequently in condition for firing.

A safety constructed as above described in no way interferes with the sight assembly, for the member N is below the bifurcated 40 member K in which is mounted the transverse pin J carrying the sight leaf. Furthermore, the safety may be manipulated more easily and conveniently than the rockable construction which has heretofore been 45 used.

What I claim as my invention is:

1. In a gun of the bolt action type, the combination with a sleeve for the bolt having an upward extension forming a mounting for the sight, of a safety transversely 50 adjustably mounted in said upward extension and engageable with the firing pin.

2. In a gun of the bolt action type, the combination with a sleeve for the bolt having an upward extension forming a mounting for the sight, of a safety in the form of a transversely slidable bar engaging an aperture in said upward extension between the sight mounting and the firing pin and engageable with the latter to lock the same.

3. In a gun of the bolt action type, the combination with a sleeve for the bolt having an upward extension forming a mounting for a sight, of a safety in the form of a 65 transversely slidable bar having a tooth on

the lower face thereof for engagement with the firing pin and being cut away at one point to clear said pin.

4. In a gun of the bolt action type, the combination with a sleeve for the bolt having an upward extension forming a mounting for a sight, of a safety in the form of a transversely adjustable bar engaging an aperture in said sight mounting and projecting beyond the same, said safety being 70 adjustable into a plurality of positions and having a tooth for engagement with the firing pin in one of said positions and cut away to clear said firing pin in another position. 75

5. In a gun of the bolt action type, the combination with a sleeve and the firing pin therein, of a safety in the form of a transversely movable bar mounted in said sleeve, said safety bar having a tooth thereon for engaging said firing pin when in one position of adjustment and being cut away to 85 clear said firing pin in another position of adjustment.

6. In a gun of the bolt action type, the combination with the bolt, the sleeve and the firing pin slidable therein, of a safety in the form of a transversely extending bar mounted in a bearing in said sleeve and projecting beyond the same, said safety bar having a tooth on one portion thereof for engaging a 90 coöperating tooth on the firing pin and being cut away at another point for clearing the firing pin. 95

7. In a gun of the bolt action type, the combination with the bolt, the sleeve and the firing pin, of a safety in the form of a transversely movable bar mounted in said sleeve, having a toothed engagement with the firing pin in one position of adjustment and cut away to clear said pin in another position of 100 adjustment, a spring pressed detent for holding said safety in its alternative positions of adjustment, and coöperating means on said safety for adjusting said detent into locking engagement with said bolt in one of 105 its positions of adjustment. 110

8. In a gun of the bolt action type, the combination with the bolt, the sleeve and the firing pin, of a safety in the form of a transversely adjustable bar mounted in said sleeve 115 and having a plurality of positions of adjustment, a spring pressed detent having one end engageable with said safety to hold the same in the different positions of adjustment and the opposite end being engageable with 120 the bolt, and coöperating means on said safety for actuating said detent into locking engagement with said bolt in one of its positions of adjustment.

9. In a gun of the bolt action type, the combination with the bolt, the sleeve and the firing pin, of a safety in the form of a transversely movable bar mounted in said sleeve, the under side of said safety having a tooth 12 portion and a cut away portion, the former 13

for locking the firing pin and the latter to provide clearance for said firing pin, a detent coöoperating with said safety for yieldably holding the same in a plurality of positions 5 of adjustment, said safety being fashioned to react upon said detent to adjust the same into different positions, one of said positions of the detent being in locking engagement with said bolt.

10 10. In a gun of the bolt action type, the combination with the bolt, the sleeve and firing pin, of a safety in the form of a transversely extending pin engaging an aperture in said sleeve, a detent engaging a longitudinal aperture in said sleeve having one end operatively engaging said safety and the opposite end engageable with the breech bolt to lock the same, and a bearing on said safety for said detent cammed to actuate the detent 15 into locking engagement with the bolt in one position of adjustment of the safety and to release the locking of the bolt in another position of the safety.

11. In a gun of the bolt action type, the combination with the bolt, the sleeve and firing pin, of a safety in the form of a transversely extending bar engaging a transverse aperture in the sleeve and having three positions of adjustment, a tooth on said safety for engaging the firing pin in two of said 20 positions of adjustment, the safety being cut away to release said pin in the third position of adjustment, a detent for yieldably holding said safety in its different positions of adjustment and having its opposite end operable into locking engagement with the bolt, and a cammed surface on said safety for engaging said detent to hold the same in locking engagement with the bolt in one position of the safety where the firing pin is also 25 locked, to release said bolt in another position where the firing pin is also released, and to release the bolt in an intermediate position where the firing pin is locked.

In testimony whereof I affix my signature. 45
FRANK A. WILLIAMS.
